Atty.

UNITED STATES PATENT OFFICE

JOHN B. CRAPO, OF EAST WAKEFIELD, NEW HAMPSHIRE

CLAMPING DEVICE

Application filed March 8, 1928. Serial No. 259,941.

The principal object of my invention is to provide an efficient, compact and easily operated device for clamping ropes or other elements and while my device is particularly useful in connection with boats and canoes it is very useful for other purposes.

A feature of my invention is the cooperation of a fixed member and a movable member to form a bite upon the rope or other member.

Another feature is a coiled spring arranged to exert strong pressure tending to hold the movable member in clamping position.

Another feature consists in simple and compact mechanism to move the movable member out of clamping position.

Other features of the invention will be pointed out below.

In the drawing

Figure 1 is a plan of a clamp embodying my invention;

Figure 2 is an elevation of the same showing also a portion of a boat;

Figure 3 is a central vertical section of the device as shown in Figure 2; and

Figure 4 is a plan similar to Figure 1, but partly broken away to show interior construction.

I show a suitable part 1 of a boat, to which part the fixed member 2 is fastened by screws 3 and 4. Member 2 has a suitable interiorly threaded perforation to receive a pivot pin described below. Member 2 is formed with a groove 5 which is curved vertically and horizontally as shown. This groove receives a portion of the rope 6 or other element and has a wall 7 at the end of the groove, which wall acts with the movable member described below to give a bite on the rope. The wall 7 is formed with a hook 8 to aid in holding the rope in the groove. The member 2 has a portion 9 sloping downwardly and outwardly instead

away the rope. This sloping edge also prevents the rope from drawing against the wood 1 of the boat and consequently prevents defacement of the wood which is a matter of consequence, as in the case of finely finished motor boats.

The threading of bolt 10 engages the threading in member 2 and the shank of the bolt is surrounded by bushing 11 which fits suitably within an opening in member 12, so that the latter is pivoted to fixed member 2. Member 12 is suitably recessed at the bottom to permit a strong coiled spring 13 to be coiled about bushing 11, one leg 14 of the spring engaging pin 15 fixed to the member 2 and the other leg 16 of the spring engaging wall 17 of the recess in member 12, said spring tending to hold the pivoted member 12 in the clamping position of Figure 1 and consequently tending to aid in prevention of movement of the rope toward the anchor or other fixed end of the rope or away from such anchor. The member 12 is made with a perforation 18 to give access to screw 3 for assembly or disassembly. The member 12 is provided with teeth to engage the rope, tooth 19 cooperating with wall 7 to give a firm bite on the rope.

A cam 20 is provided within the recess in member 12 and has fixed connection with a shank 21 which has a circular portion passing through a perforation in member 12 located between the pivot of member 12 and the free end of member 12, the upper portion of the shank being rectangular in cross section. Upon this rectangular portion is mounted a lever or handle 22 which has an interior opening to fit the rectangular portion of the shank to provide for turning of the shank and consequently turning of the cam. A pin 23, passing through the handle and engaging the shank, is provided to prevent vertical movement of the handle. The periphery of the cam engages pin 24 which is fixed to the member 2 so that when

the handle 22 is moved upwardly in Figure 4 member 12 will be moved away from clamping position and this movement may be continued until notch 25 in the periphery of the cam engages pin 24 and then the cam 5 will be held in that position which is the inoperative or unclamped position of member 12. The user of the device may then use both hands for manipulation of the rope.

10 What I claim is:

1. A device of the character described comprising a fixed member and a pivoted member, one of said members having a groove for a rope or the like and a wall at 15 the end of the groove and the other of said members having a projection, said wall and said projection forming a bite upon the rope or the like when the pivoted member is in clamping position; and means to hold 20 the pivoted member in clamping position.

2. A device of the character described comprising a fixed member; a pivoted member having a recess; and a coiled spring having two legs within said recess, one leg 25 engaging the fixed member and the other leg engaging the pivoted member to hold 30 the latter in clamping position.

3. A device of the character described comprising a fixed member, a pivoted member; resilient means tending to hold said pivoted member in clamping position; and a cam mounted on the pivoted member and having its periphery in operative engagement 35 with the fixed member to move the pivoted member out of clamping position.

4. A device of the character described comprising a fixed member; a pivoted member; resilient means tending to hold said pivoted member in clamping position; and 40 a cam mounted on the pivoted member and having its periphery in operative engagement with the fixed member to move the pivoted member out of clamping position; and means to hold the cam against movement 45 when the pivoted member is in the desired inoperative position.

5. A device of the character described comprising a fixed member; a pivoted member; resilient means tending to hold said pivoted member in clamping position; a cam pivoted on said pivoted member between the pivot and free end of the pivoted member, said cam having its periphery in operative engagement with the fixed member 55 and being located beneath the pivoted member; and a lever above the pivoted member and having fixed connection with the cam to operate the latter.

6. A device of the character described comprising a fixed member having a portion sloping downwardly and outwardly; a pivoted member to cooperate with the fixed member; and means to hold the pivoted member 60 in clamping position, said sloping

portion being located adjacent to the edge of the fixed member.

7. A device of the character described comprising a fixed member; a screw to hold said fixed member to a support; a pivoted member movable across the head of said screw and having an opening to give access to said screw head when the pivoted member is in its non-clamping position; and means to hold the pivoted member in clamping position with relation to the fixed member.
